ANGLING AND LOCKING ARRANGEMENT FOR VEHICULAR MOUNTED PLOW ATTACHMENTS

William W. King, Cleveland, Ohio, assignor to Meyer

Products, Inc., Cleveland, Ohio

Filed Dec. 21, 1964, Ser. No. 420,039

9 Claims. (Cl. 37—42)

ABSTRACT OF THE DISCLOSURE

The disclosure pertains to the art of vehicular plow blade attachments of the type including a locking and release mechanism which may be actuated to permit horizontal angular adjustment of the plow blade. The mechanism includes a horizontal plate attached to the back of the plow blade which is movable relative to a locking member mounted on a yoke fastened on the front of the vehicle which supports the plow blade. The horizontal plate has an arcuately formed edge with circumferentially spaced radial notches therein adapted to receive a shear pin entering directly from the rear to lock the blade in a predetermined angular relationship.

This invention pertains to the art of vehicle mounted plow blade attachments and more particularly to a new and improved blade angle and lock adjustment therefor.

The invention is particularly adapted to and will be described with particular reference to a plow blade attachment where it is necessary to periodically change the angles of the blade relative to its supporting vehicle.

It is customary to mount snow plow attachments or the like on the front of specially adapted motorized vehicles so that the attachment can be raised or lowered with respect to the ground to adjust the vertical position of the plow blade. It is also common to permit angulation of the plow blade in a horizontal plane.

The latter adjustment may not necessarily be controlled from the cab of the vehicle and is often set at the start of operation. Any subsequent change in the blade angle requires that the operator dismount and manually change the blade angle.

In the usual arrangement, the plow blade is rigidly mounted on a yoke that is pivoted relative to a frame member having a series of circumferentially spaced holes therein. The yoke has a corresponding set of holes and by angling the blade, two holes may be aligned to receive a metal shear pin thus to lock the blade in the desired angular position while at the same time providing a safety yield point that will release the blade when a turning force is received in excess of a predetermined value.

Two problems are presented with this arrangement. Aligning the openings exactly to receive the pin is difficult in actual service conditions. Secondly, removal of the old pin may be difficult due to the presence of ice or snow or to burrs resulting from the shearing off of the pin.

The present invention contemplates a new and improved blade angling and locking arrangement which overcomes all these difficulties and others.

In accordance with the invention the angling and locking arrangement comprises a member having a curved, notched edge and a latch member radially movable into and out of the notches, one of the members being mounted on the blade movable relative to the other mounted on the vehicle with the blade pivot axis as a center.

Further in accordance with the invention the latch member is normally biased toward the notches but can be restrained in one position out of engagement therewith and the blade can be freely angled with the latch member in the restrained position, but when released the latch

2

member automatically locks into engagement with the curved edge member. In the event the blade is angled too far or not enough, the latch member when released may not drop into one of the notches of the curved edge, then in accordance with the invention, additional angling of the blade results in the latch member snap-locking with one of the notches when brought into alignment with it.

Further in accordance with the invention the curved edge of the one member is guided in a horizontally extending slot of a mounting assembly and the latch member includes a radially movable shear pin positionable vertically through the slot when in registry with one of the notches.

Further in accordance with the invention, the shear pin is segmented along its length with each segment being approximately equal to the vertical width of the horizontal slot, the segments tending to shear without leaving burrs or causing the shear pin to bend when a turning force on the blade is received in excess of a predetermined value.

Further in accordance with the invention and particularly where a segmented shear pin is used, the latching member includes a tubular housing adapted to hold the shear pin and an element cooperating with the tubular housing and shear pin for vertically adjusting the pin height with respect to the horizontal slot.

The invention has as one of its objects a plow angling and locking arrangement which is inexpensive to manufacture, readily adaptable to existing plow attachments, will reduce wear of parts and permit more rapid angulation and locking of the blade under operating conditions.

Another object is the provision of a blade angling and locking arrangement in which a latch member is radially movable into and out of locking engagement rather than being pulled axially through aligned holes thereby facilitating rapid blade angling.

Another object is to provide a blade angling and locking arrangement including a latch member spring biased into locking engagement in combination with means for holding the member out of locking engagement thus making it easier to adjust the blade angle when required.

Another object is to provide an elongated shear pin and mounting arrangement whereby a single shear pin may be used a plurality of times before a new one is required.

Another object is to provide a shear pin divided into a plurality of segments which will shear from the body of the pin cleanly and without appreciable bending.

These and other objects will be more fully appreciated by referring to the following description and drawings wherein:

FIGURE 1 is a fragmentary plan view of a plow attachment incorporating a preferred embodiment of the invention;

FIGURE 2 is a side elevational view of the attachment shown in FIGURE 1;

FIGURE 3 is an enlarged fragmentary sectional view showing the preferred embodiment of the invention in the blade locking position; and

FIGURE 4 is an offset sectional view taken along line 60 4—4 of FIGURE 3.

Referring now to the drawings wherein the showings are for the purpose of illustrating a preferred embodiment of the invention only and not for the purpose of limiting same, FIGURES 1 and 2 show a plow blade attachment 10 comprising a plow blade 12 pivotally supported at 14 on a yoke member 16 which in turn is adapted to be pivotally mounted at 18 to a motorized vehicle. Springs 20 are tension springs to retract the blade after striking an immovable object below the blade horizontal pivot 18.

As is standard with articulated plow attachments of the type illustrated, the blade 12 can also be angled in a

horizontal plane and in accordance with the invention, the blade 12 is angled with respect to the yoke member 16 by means of a blade angling and locking mechanism indicated generally by the numeral 22. The mechanism 22 includes a plate member 25 mounted on the blade and having an arcuate edge 27 formed with a plurality of circumferentially spaced, radially extending notches 29 therein. While the notches 29 are shown as being rectangular in the preferred embodiment of the invention, it should be understood that almost any type of recess or groove in the edge 27 can be used so long as there is an unobstructed rear access as will be made clear hereinafter.

Referring now to FIGURES 3 and 4, the mechanism 22 also includes a mounting and latch assembly 31. The assembly 31 includes a guide block 32 formed by horizontally extending elements 33 and 34 vertically spaced apart to define a horizontal slot 35 adapted to slidably receive the plate 25. A vertical slot 37 in the elements 33, 34 is of the same general size and shape as the notches 29 in the plate member 25 and opens in a radial direction for an unobstructed access from the rear in general alignment with the blade pivot 14.

The assembly 31 also includes a lever arrangement 50 which comprises a bifurcated lever 51 pivoted at 52 for movement in a vertical plane in alignment with the slot 37 by means of a handle 53 welded to the outer end of the lever 51. An arm 55 is pivotally mounted at 57 near the outer end of the lever 51 and extends through an enlarged opening 59 in a vertically extending wall 60. A spring element 61 bears against the wall 60 to bias the arm 55 and thus the lever 51 in a counterclockwise direction about the pivot 52 as viewed in FIGURE 3.

Below the lever 51 is a bracket 63 mounted on the wall 60 and extending horizontally outwardly to provide a pivot 65 for mounting a tubular housing 67. The tubular housing 67 is arranged for movement in the vertical plane of the slot 37 and extends vertically through the bifurcated lever 51 where it is freely guided therein by a pair of dogs 69 on the inner surface of sides of the lever. Arranged within the tubular housing 67 is a flexible strap 70 which is bent to conform to the interior of the housing 67 and provide a bottom 71 therefor, the free end 73 above the top of the housing 67 being bent outwardly to provide an adjustable depth for the bottom 71 for reasons appearing hereinafter.

A pin 75 rests against the bottom 71 of the tubular housing 67 and extends vertically through the slot 37 when in the locking position as shown in FIGURE 3 and is adapted to register with one of the radially extending notches 29 of the movable plate member 25. The pin 75, like notches 29, preferably has a rectangular cross-sectional shape and is formed of a metal having a lower shear modulus than the material of either the plate member 25 or the guide block 32. The rectangular shape allows the pin's flat sides to bear against the flat sides of a notch 29 and slot 37 thus lessening the wear on the pin and other parts. Of course any cross-sectional shape may be employed without departing from the invention, but a flat-against-flat wearing arrangement is preferred. In addition the pin 75 may be segmented by means of notches 77 on opposite sides thereof thus defining a plurality of shear segments 80 throughout substantially the entire axial length. The pin is vertically elevated so that at least one segment 80 is disposed in the horizontal slot 35 of the guide block 32. However, notches 77 may be unnecessary as explained hereinafter.

In operation when the operator desires to change the angle of the plow blade 12, it is raised above the ground and the handle 53 is lifted thus swinging lever 51 in a clockwise manner as viewed in FIGURE 3 about its pivot 52. This movement causes dogs 69 to engage the tubular housing 67 substantially above its pivot 65 thus causing it with the pin 75 therein to rotate out of the locking position with notch 29 thus unlocking the movable plate member 25. This movement also causes the pivoted end of lever 55 to swing outwardly and down-

wardly against the force of spring 61 thereby decreasing the opposing moment arm acting on lever 51 due to spring 61. When the handle 53 has been raised sufficiently to tilt the pin 75 to the dot-dash position outlined in FIGURE 3, the pivoted end of the arm 55 will have been pulled downwardly a sufficient amount relative to the pivot 52 of lever 51 to cause an over center condition with respect to spring 61 whereby it remains compressed but does not bias the bifurcated lever 51 and tubular housing 67 in the locking direction.

The operator can now rotate the blade 12 to the desired angle so that a notch 29 approximately registers with the slot 37. The over center condition of spring 61 is then released by moving the handle 53 down. The pin 75 springs into locking position against the plate 25 passing through the slot 37 and into registration with one of the notches 29. This greatly facilitates the speed of plow angling over the prior art where it was necessary to sight down through a pair of holes in order to insert the locking pin. With the present invention even a slight misalignment is of no consequence, since the pin 75 is spring biased toward the locked position. In other words, if upon being released, the pin strikes the edge 27 of plate 25 instead of fitting within a notch 29, it is only necessary for the operator to rotate the blade 12 in the proper direction until a notch 29 becomes aligned with the slot 37 whereupon the pin 75 automatically snaps into locked position.

The pin 75 is preferably expendable and upon relative movement of the plate member 25 with respect to the guide block 32 due to an excessive turning force on the blade 12, the pin 75 will be sheared. To minimize bending or burring of the pin 75, it is divided into shear segments 80 separated by planes of weakness through the pin. However, if the pin is soft enough, the notches 77 can be eliminated and a completely smooth pin used without excessive bending or burring because the pin is held in two plates while shearing takes place. That is, the guide block elements 33, 34 hold the pin at axially spaced locations while the plate 25 shears it in between.

When the pin 75 is sheared, it will be considerably shortened and obviously will not reach to the required vertical height to provide locking engagement with the plate 25. Thus, in accordance with the invention, the pin is longer than otherwise required and may be extended from within the housing 67 by adjusting the flexible strap 70 so that the bottom 71 is raised sufficiently to compensate for the foreshortened condition of the pin.

Having thus described a preferred embodiment of the invention and its method of operation it will be appreciated that numerous modifications and changes can be made which would be obvious to those skilled in the art without departing from the invention as defined by the appended claims insofar as they are limited by the prior art.

Having thus described my invention, I claim:

1. In combination with an angularly adjustable plow blade, adjustment and locking means comprising a horizontal plate member having an arcuate edge and being mounted on the blade for angular movement therewith, the edge being spaced from the blade pivot and having circumferentially spaced, radially extending notches therein, locking means positioned adjacent the plate member defining a horizontal guide channel for slidably receiving said arcuate edge, said channel having an unobstructed vertical slot formed therein aligned with the blade pivot and extending radially inwardly in registration with one of said notches, a pin member pivoted relative to said channel in alignment with said slot and extending vertically beyond said plate member and spring means for biasing said pin member into locking engagement with said plate member when one of said notches is aligned with said slot.

2. The combination as set forth in claim 1 wherein said pin member is made of a relatively soft material having a shear modulus substantially less than the material forming said plate member and guide channel so as to permit forceable blade movement by shearing the pin when a predetermined turning force on the blade is exceeded, the pin being held in two places by the guide channel to minimize bending of the pin member.

3. The combination as set forth in claim 2 wherein the pin member has a flat wearing surface engageable with the side of said slot.

4. The combination as set forth in claim 3 wherein the notches, slot, and pin member are rectangular in cross-sectional shape.

5. The combination as set forth in claim 1 wherein the pin is divided into shear segments throughout its length, one of said segments being positioned with said horizontal channel when the height of said pin is properly adjusted.

6. In combination with an angularly adjustable plow blade pivotally mounted on a frame, adjustment and locking means comprising

a horizontal plate member having an arcuately formed edge spaced from the blade pivot and having circumferentially spaced radially extending notches therein, a locking member positioned adjacent the plate member including pin means movable in the radial plane of said edge for releasably engaging said plate member at one of said notches, and

a horizontally extending mounting element in slidable engagement with the plate member and having a slot formed therein adapted to register with one of said notches, said slot having an unobstructed access aligned with said pin means to permit radial unlocking movement thereof, one of said members being mounted on the frame and the other being movable with said blade for relative arcuate movement with respect to each other.

7. The combination as set forth in claim 6 wherein the pin means is formed of a material having a substantially lower shear modulus than that of either the plate member or mounting element so as to permit relative movement of said members when a turning force is exerted on said blade in excess of a predetermined value.

8. The combination as set forth in claim 7 wherein said locking member comprises in addition

10 a tubular member for housing said pin means which is pivotally mounted for movement in a vertical plane aligned with said slot, length adjustment means cooperating with said tubular member and pin means for adjustably extending the pin means vertically relative to the tubular member so that the top of the pin means is above the plane of said arcuately formed edge, and spring means biasing said tubular member and pin means toward the locking position with said plate member.

15 20 25 9. The combination as set forth in claim 8 wherein said spring means comprises spring biased lever means pivotally mounted for engagement with the tubular member and urging said tubular member and pin means into locking engagement except in one position, the biasing force being inoperative in said one position due to the angular position of said lever means.
